UNITED STATES PATENT OFFICE.

HENRY ESSEX, OF HAVERSTRAW, NEW YORK, ASSIGNOR TO THOMAS H. BATES, OF NEW YORK, N. Y.

SEWING-NEEDLE.

Specification of Letters Patent No. 31,000, dated December 18, 1860.

To all whom it may concern:

Be it known that I, HENRY ESSEX, of Haverstraw, in the county of Rockland and State of New York, have invented a new 5 and useful Improvement in Sewing-Needles; and I do hereby declare that the following is a full, clear, and exact description thereof, reference being had to the accompanying drawings, making part of this specification, in which—

Figure 1 is a perspective view of the improved needle. Fig. 2 shows two sides of a three sided needle. Fig. 3 is a transverse section taken through the angular portion 15 of a needle.

Similar letters of reference indicate corresponding parts in the three figures.

This invention is applicable to needles for all ordinary kinds of sewing by hand. It 20 consists in giving to needles a triangular form in the body, or middle portion, but retaining the usual round form at and near the eye and point.

The object of the invention is to give the 25 needles greater strength without giving them greater substance.

The drawings fully illustrate the form of a needle of this kind. The triangular portion may be generally about half the length 30 of the needle, or somewhat more or less, and extend to within about the same distance from the head and point. The best manner of obtaining the triangular form is by swaging the wire, from which the needles are 35 to be made, in a suitable die placed under a suitable hammer or drop, after which the grinding is performed in such a manner as to preserve the triangular form of the body, but to produce a round form at and near 40 the point and head. The wire is not in-

tended to be reduced in bulk by the swaging, but the triangular portion should contain about the same amount of metal as if it were round like the other portions of the needle. The edges of the triangular portion are not intended to be sharp as the form is not given to make them cut the material upon which they are used.

Repeated experiments with needles of this improved form, and needles of the ordinary 50 form, made of the same wire and hardened and tempered in the same way, show conclusively that those of the improved form are much stronger than those of the ordinary form. My improved needles also pass 55 through the cloth more easily, there being less friction, than with the common needle. My improved needle also presents a better surface, because flattened, for the fingers of the user to take hold upon. Therefore 60 my improved needle facilitates and expedites the labor of sewing.

I am aware that needles have been made of a triangular form at and near the point; and therefore I do not claim making any 65 portion of a needle triangular except when the triangular and round portions are arranged substantially as herein above specified, but

Having thus described my invention, I 70 claim and desire to secure by Letters Patent as an improved article of manufacture—

A sewing needle having a cylindrical head and point and a body of triangular or three sided form, as herein shown and described. 75

HENRY ESSEX.
